UNITED STATES PATENT OFFICE.

CHARLES E. WILLIAMS, OF NATICK, MASSACHUSETTS.

AUDIPHONE-TRANSMITTER.

No. 911,101.

Specification of Letters Patent.

Patented Feb. 2, 1909.

Application filed August 6, 1907. Serial No. 387,318.

To all whom it may concern:

Be it known that I, CHARLES E. WILLIAMS, a citizen of the United States, and resident of Natick, in the county of Middlesex and State 5 of Massachusetts, have invented an Improvement in Audiphone-Transmitters, of which the following description, in connection with the accompanying drawings, is a specification, like letters on the drawings representing like 10 parts.

The object of my invention is to secure clear and more pronounced articulation in the transmission of speech, and greater definition in the transmission of other sounds.

In its general elements my transmitter consists of the usual parts, but I have discovered that, by having an open electrode by providing holes clear through the electrode, instead of simply providing the electrode 20 with cup-shaped openings, for holding the carbon particles or minute spheres, and by providing an exceedingly thin barrier at the front end of these holes, simply sufficient to prevent the particles from falling out, and 25 by placing the diaphragm at the back of the instrument instead of at the front, and by providing a reverberatory chamber at the front of the instrument, my object is attained in a remarkable degree.

Accordingly, my invention resides, not only in providing an instrument with all the above features, but it resides in each of said features taken individually, as each feature mentioned above contributes to that extent 35 a distinct step in advance, and, while I prefer to embody all the features of improvement in one instrument, yet advantageous results may be obtained from each taken separately, or from part only taken together.

Besides the above more important features, my invention includes certain others, which are set forth in connection with the following description of my invention in its preferred details, reference being had to the 45 accompanying drawings for clearness of understanding.

In the drawings, in which I have shown the preferred embodiment of my invention, Figure 1 shows the transmitter in edge elevation, Fig. 2 in front elevation, Fig. 3 in central vertical section; Figs. 4 and 5 are transverse sectional details of different forms of reverberatory chambers; Figs. 6 and 7 show respectively in central vertical section and front elevation and rear elevation a 55 different embodiment of my invention, the

latter figure having certain parts omitted to show the internal construction; Fig. 8 is a view in plan showing the paper disk for retaining the gauze holder, which is similarly 60 shown in Fig. 10; Fig. 9 is an enlarged fragmentary view in central vertical section to show more distinctly the construction and operation of the central electrode.

My instrument proper consists essentially 65 of an electrode 1 supported centrally at the back side of a reverberatory chamber 2, whose front side 3 constitutes the wall against which the spoken sound to be transmitted is directed, and a diaphragm 4 supported at the 70 rear side of the electrode 1 for completing, in connection with suitable circuit wires or connections, the usual electrical circuit for conveying the wave impulses. The electrode 1 is provided with suitable circuit - closing 75 granules or particles, preferably in the form of small carbon spheres or balls 5, but, instead of having these particles simply in a cavity in the electrode, the latter is provided with perforations 6, as best shown in Fig. 9, 80 which extend entirely through the carbon button which constitutes the electrode 1. At their front ends the holes 6 are closed by an exceedingly light and thin wall 7. I have found gauze-like material, like chiffon, 85 well adapted for this purpose. For convenience I stretch a piece of the chiffon or gauze wall across the front side of the electrode 1 and secure it by any suitable means, either pasting it directly to the electrode 1 or clamping it in position by means of a paper disk 8, shown best in Fig. 8, perforated at 9 to correspond with the holes 6, so as not to interfere in any way with the free thin walls 7. As shown in Fig. 9, an insulating plate 10 is interposed between the electrode 1 and its 90 middle support 11, to which it is secured by any suitable means, as a screw 12 properly insulated therefrom, as shown in detail in Fig. 9. The support 11 is herein shown as 95 provided with a plurality of perforations 13 in line with the holes 6 and with openings 14 for permitting still freer movement of the sound waves, and extends outwardly to receive a part 15 of the supporting case in Fig. 105 3, and a peripheral portion, to which is secured by any suitable means, as by screws 16, Fig. 3, the reverberatory chamber 2.

In Fig. 6 the reverberatory chamber is secured by a metal arm 17. The reverberatory chamber may be composed of hard rubber, metal, or other substance, according to

the tone desired. I prefer not to make the reverberatory chamber integral with the case, as it is desirable to be able to change the chamber, Figs. 4 and 5 showing different shapes and sizes of reverberatory chambers placed on the instrument. This reverberatory chamber constitutes an additional chamber made of resonant material located at the front of the electrode chamber, openings 13 or 14, or both, extending between said two chambers, so that sound waves may pass from one chamber to the other, or from the reverberatory chamber through openings in the intervening wall 11 into or through the electrode openings or cells 6 to the globular carbons 5 and the diaphragm 4. Practical experience demonstrates that ear-phones have to be made or set to different tones and pitches for different persons to enable them to hear. One person can hear better with a high, sharp sound, another can hear better at a low pitch and a rounder or fuller tone. I get this adjustability on the same instrument by changing the reverberatory chamber, making it larger or smaller and of different shape according to the degree or character of the deafness of the person who is to use it. Accordingly, it will be at once evident that having the reverberatory chambers made removable or adjustable is a great advantage to the dealer, as well as to the manufacturer. Not only are the walls of the electrode chamber and the reverberatory chamber of resilient or resonant material to receive the sound waves from without, but, as they are completely closed or air-tight, the vibration fills them with sound waves, which are thereby amplified by this confinement and the material composing the walls.

By securing the electrode to the wall between the two chambers, I obtain a rigidity which is of importance in securing strong electrical variations or sharp transmission of the sound waves. By having a few openings 13 in said intervening wall, in addition to the openings through the electrode, I obtain a better articulation than with a great number of said openings. By having the reverberatory chamber at the front and the open side of the diaphragm at the back, I get a more sensitive diaphragm action, as fewer of the globular carbons 5 may be used. The instrument, when in use on the person, naturally inclines backwards, and hence, by having the diaphragm at the rear, the carbons naturally rest lightly against the diaphragm, or heap up as shown in Fig. 9, whereas if the diaphragm were in front the carbons would be falling away from the diaphragm, and a greater quantity would therefore necessarily be required, or else the cells made at an angle in order to force the carbons forward against the diaphragm, and said angular position of the cells would prevent the instrument from being as sensitive to the sound

waves as the preferred construction shown. By having the cells or perforations of the carbon button 1 open, I obtain a freer movement of the spherical carbons and allow the sound waves to act more freely and directly upon the carbons and upon the center of the diaphragm. This takes place at the precise moment that the ethereal waves are being converted into electrical sound waves, and thereby conduces still further to sharpness and clearness of articulation. The fine wire or cloth gauze 7 permits the free passage of the air or sound waves. Preferably also I admit the sound waves simultaneously to the opposite or back side of the diaphragm 4, this being accomplished by providing at the back side of the instrument a cover or protector 18 in the form of a sounding board secured by any suitable means to the rim 15 of the casing, as by means of a threaded flange 19, Fig. 3, the electrode chamber being surrounded by an annular air space 20 opening toward the front by means of openings 21 at intervals through the peripheral portions of the instrument, said openings, however, not connecting in any way whatever with the reverberatory chamber 2, which, as stated, is closed. By this means that portion of the sound waves which strikes against the im-perforate wall 3 sets up amplified waves in the confined air space of the reverberatory chamber and the electrode chamber, while that portion which strikes the perimeter of the instrument enters through the openings 21 into the open air space 20, and upon striking the sounding board 18 is deflected against the back side of the diaphragm 4, co-operating with the waves which strike against the front side of said diaphragm. I will not undertake to explain the theory of operation of this portion of the device, as it is possible that the rear chamber inclosed by the sounding board 18 also acts as a reverberatory chamber, but the fact is that by employing it much clearer articulation results.

In Fig. 6 I have shown the sounding board 18 as concavo-convex, and secured by screws 22 to the wall of the electrode chamber, a hard rubber ring 23 closing the edges of the instrument between said front side and said sounding board. The projecting edges 24 of the sounding board catch and are influenced by a portion of the sound waves, but the sounding board is influenced mainly by the sound waves which pass through the openings 25, 26 in the front part of the instrument, as shown clearly in Fig. 7. A hook 27, or any other suitable means of supporting the instrument may be provided. The circuit wires are shown at 28, 29, one leading from the diaphragm and the other from the central carbon, as usual in this class of instruments.

As already intimated, my invention may have a wide variety of mechanical embodi-

ments. Not only do I intend to claim broadly as my invention the arrangement of the central carbon and the reverberatory chamber, but also the placing of the diaphragm at the back and front, providing an imperforate front for receiving and transmitting the sound. Also various other features are herein claimed. The sounding board feature is not herein claimed broadly, 5 as it forms the subject matter of a copending application, in which I have shown different species of the generic invention.

Having described my invention, what I claim as new, and desire to secure by Letters 10 Patent, is:

1. An audiphone transmitter, provided with means for transmitting sound waves electrically, and having a closed reverberatory chamber at its front side for receiving 20 and amplifying the sound waves, and for conveying them to said transmitting means.

2. An audiphone transmitter, provided with means for transmitting sound waves electrically, and having a closed reverberatory chamber removably secured at its front 25 side for receiving and amplifying the sound waves, and for conveying them to said transmitting means.

3. An audiphone transmitter, provided 30 with means for transmitting sound waves electrically, including a diaphragm at the rear of the instrument and loose granular circuit-closing means against the front side of said diaphragm, and having an imperforate front side for receiving the sound 35 waves and transmitting them to said diaphragm, the interior of the instrument enclosed between said diaphragm and front wall being air-tight for amplifying the sound 40 waves transmitted.

4. An audiphone transmitter, having a wave-transmitting diaphragm located at its back, means including a reverberatory chamber at its front for receiving the sound waves 45 and directing them against the front of the diaphragm, and intervening means coöperating with said diaphragm in converting the sound waves into electrical waves, including granular circuit-closing means arranged to 50 rest loosely against the front of said diaphragm.

5. An audiphone transmitter, having a wave-transmitting diaphragm located at its back, means at its front for receiving the 55 sound waves, and intervening means coöperating with said diaphragm in converting the sound waves into electrical waves, including a perforated button, granular circuit-closing means contained in said perforated 60 button in position to rest at one end against said diaphragm, and a thin barrier at the opposite end of the button for retaining said granular means while permitting the passage of sound waves.

6. An audiphone transmitter, having a re-

ceiving and transmitting diaphragm, a central button transversely perforated mounted endwise adjacent one side of said diaphragm, granular electrodes carried by said perforated button to rest loosely against said diaphragm at one end of the button, and a thin perforate wall closing the button at the opposite end for holding said carbons in while permitting free passage of the air. 70

7. An audiphone transmitter, having a receiving and transmitting diaphragm, a central button transversely perforated mounted endwise adjacent one side of said diaphragm, granular electrodes carried by said perforated button to rest loosely against said diaphragm at one end of the button, and a thin perforate wall of gauze closing the button at the opposite end for holding said carbons in while permitting free passage of the air. 75

8. An audiphone transmitter, having a receiving and transmitting diaphragm, a central button transversely perforated mounted endwise adjacent one side of said diaphragm, granular electrodes carried by said perforated button to rest loosely against said diaphragm at one end of the button, and a thin perforate wall of gauze and a retaining ring secured against said gauze and perforated to register with said button closing the button at the opposite end for holding said carbons 90 in while permitting free passage of the air. 95

9. An audiphone transmitter, comprising an electrode chamber and a reverberatory chamber, a diaphragm closing the rear side of the electrode chamber, a rigid wall separating said chambers, and a button secured rigidly to said intervening wall next to said diaphragm, and granular electrodes loosely held by said button to engage said diaphragm. 100

10. An audiphone transmitter, comprising an electrode chamber and a reverberatory chamber, a diaphragm closing the rear side of the electrode chamber, a wall separating said chambers, and a button secured to said intervening wall next to said diaphragm, and granular electrodes loosely held by said button to engage said diaphragm, said wall and button being transversely perforated to hold said granular electrodes, and said wall having other perforations affording air communication between said two chambers. 110

11. An audiphone transmitter, having transmission mechanism for converting the sound waves into electrical waves, including a diaphragm and granular electrodes in position to rest loosely against said diaphragm, and means permitting the sound waves to act directly upon said electrodes at the instant the sound waves are being converted into electrical waves. 120

12. An audiphone transmitter, having mechanism for receiving the sound waves, and transmission mechanism including a diaphragm for converting the sound waves into electrical waves. 125

electrical waves, said receiving mechanism including means for conveying the sound waves directly to the front side of the diaphragm and means for conveying the sound waves directly to the back side of the diaphragm.

13. An audiphone transmitter, having mechanism for receiving the sound waves, and transmission mechanism including a diaphragm for converting the sound waves into electrical waves, said receiving mechanism including means for conveying the sound waves directly to the front side of the dia-

phragm and means for conveying the sound waves directly to the back side of the dia- 15 phragm, the latter means including a sounding board at the back of the instrument and an annular air space about the instrument having openings through the front side.

In testimony whereof I have signed my 20 name to this specification, in the presence of two subscribing witnesses.

CHARLES E. WILLIAMS.
